Primary Examiner — Eric Goodman*Assistant Examiner* — Luqman McNeil(74) *Attorney, Agent, or Firm* — Ladas & Parry LLP(57) **CLAIM**

We claim the ornamental design for a washing machine, as shown.

DESCRIPTION

FIG. 1 is a front/right-side/top perspective view of a washing machine showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof;

FIG. 7 is a bottom-side elevational view thereof; and,

FIG. 8 is a referenced view thereof.

Features shown in broken lines are disclaimed and form no part of the claimed design.

1 Claim, 7 Drawing Sheets(56)
